UNITED STATES PATENT OFFICE.

HARRIET G. BUFFINGTON, OF OLD SAYBROOK, CONNECTICUT.

SHIELD FOR STOVES.

Application filed March 14, 1922. Serial No. 542,637.

To all whom it may concern:

Be it known that I, HARRIET G. BUFFINGTON, a citizen of the United States, residing at Old Saybrook, in the county of 5 Middlesex and state of Connecticut, have invented new and useful Improvements in Shields for Stoves, of which the following is a specification.

This invention relates to protective shields 10 or casings for stoves and has for its object the provision of a novel device in the nature of a shield which is designed to be set up wherever an oil or other similar stove is to be used and which is for the purpose of 15 preventing excessive heat generated by the stove from injuring the walls or wood work of the building in which the stove is located, the device being so constructed as to entirely contain or surround the stove.

20 An important and more specific object is the provision of a protective device of this character which includes a solid rather heavy base which has the advantage of rendering the device stable and preventing its casual 25 upsetting through any cause, this base being formed with a bowl for catching the oil in case the stove explodes and being, moreover, provided with means engaging the stove legs for holding the stove stationary 30 with respect to the device.

Another object is the provision of a device of this character which is formed as a rectangular casing constructed of wire and having guides within which may be slid 35 sheets of asbestos or the like which on account of its well known heat insulating properties is highly advantageous for use in this connection for preventing the burning of the walls or woodwork of the building around 40 a stove.

Still another object is the provision of a protective device of this character in which any or all of the sheets of asbestos may be removed if desired and in which all of the 45 sheets may be placed in position in case the stove catches on fire and it is desired to smother the fire or protect the surrounding walls from injury.

An additional object is the provision of 50 a device of this character which will be simple and inexpensive in manufacture, highly efficient in use, durable in service and a general improvement in the art.

With the above and other objects and advantages in view, the invention consists in 55 the details of construction to be hereinafter

more fully described and claimed and illustrated in the accompanying drawing in which

Figure 1 is a perspective view of the device, the top member being removed and the 60 door closed.

Figure 2 is a vertical sectional view with the top in position,

Figure 3 is a horizontal sectional view 65 likewise with the door closed,

Figure 4 is a perspective view of the base alone, and

Figure 5 is a detail section through the base.

Referring more particularly to the drawing I have shown my device as comprising a heavy base 10 of suitable material such as cast iron or the like and which is here shown as being rectangular in shape though it should be understood that any other shape 70 may be used if found advantageous or preferable. This base 10 is provided near its corners with holes 11 within which are suitably secured upright rods 12 which are connected at their upper ends by horizontal rods 80 13 which may be integral therewith and which define a rectangular cage structure. Three of the frames formed by the wires 12 and 13 are covered with wire screens indicated at 14 and the remaining side or 85 frame of the device is hinged as indicated at 15 whereby to provide a door which may be opened for the purpose of placing the stove within the device. This door, designated by the numeral 16 is likewise covered 90 with wire mesh and is also provided with any suitable catch device indicated at 17.

The horizontal rods 13 are provided with horizontal guides 18 which provide retaining means for the upper ends of a plurality 95 of sheets 19 of asbestos which may be slid into position between the guides for the purpose of entirely enclosing the sides of the device and forming a protective casing which will operate to prevent injury to the 100 wall or woodwork on account of the heat from the stove. The lower ends of these sheets are engaged within grooves 20 formed in the base. Extending upwardly from the members 18 are guides 21 which form 105 retaining means for a top asbestos sheet 22 which may be placed in position to form an entirely closed cage which will smother a fire in case of explosion.

The base is preferably provided at opposite sides with handles 23 and is formed centrally with a base or bowl 24 which is

for the purpose of catching any oil which may be spilled at any time and particularly in the event of an explosion. The top surface of the base is furthermore provided 5 with a plurality of arcuate slots or recesses 25 which are designed for the legs of a stove and which are formed with overhanging flanges 26 which will engage over the feet of the stove and prevent the stove from 10 being upset when the device is moved about.

In the use of the device it will be seen that if the door is open the oil stove or other stove to be used may readily be placed within the device with its legs engaged 15 within the recesses after which the door is closed and held shut by means of the catch 17. In case one portion of the cage is disposed toward and comparatively close to the wall of woodwork of a building or room 20 it is apparent that one or more of the sheets 19 of asbestos may be engaged in position for the purpose of protecting the wall and woodwork against the excessive heat generated by the stove. Also in case it is so 25 desired, all of the sheets may be placed in position except the one at the top whereupon the stove will burn perfectly satisfactorily. In case it is desired even the top sheet may be placed in position and this 30 will naturally operate to smother the fire and put out the flame. If the top sheet is omitted, the device may be conveniently used as an umbrella rack the bowl operating to catch the water dripping from a wet umbrella.

From the foregoing description and a study of the drawing it will be apparent that I have thus provided a simply constructed and consequently inexpensive safety 40 device which will be of material advantage to users of oil and other similar stoves inasmuch as it will of course protect and prevent injury to woodwork and walls adjacent the stove. It is also to be noted that the 45 device will be of distinct advantage in smothering an undesired fire and preventing it from spreading.

While I have shown and described the preferred embodiment of the invention it

is of course to be understood that I reserve 50 the right to make such changes in the form, construction and arrangement of parts as will not depart from the spirit of the invention or the scope of the subjoined claims.

Having thus described my invention I 55 claim;

1. A protective device of the character described comprising a base, a plurality of upright frames rising from said base, all but one of said frames being covered with 60 wire screen, a swingably mounted frame closing the remaining side of the cage structure thus defined and constituting a door, horizontally extending guide members at the upper ends of said frames, guides on said 65 base, and panels removably engaged within the respective guides.

2. A device of the character described comprising a base, a plurality of upright frames secured to said base and covered with 70 wire screen to define a cage having one side open, a screen covered door normally closing the remaining side of the cage, horizontally disposed guide members at the upper ends of said frames and said door, the top surface of the base being formed with grooves located outwardly of said frames and panels removably engaged through said guides and within said grooves.

3. A protective device of the character 80 described comprising a base provided at its corners with holes, a plurality of upright rods secured within said holes, horizontal rods connecting the upper ends of said upright rods and defining a rectangular cage, 85 the top and all the sides but one of the cage being covered with wire screen, a door covered with wire screen hinged upon and closing the remaining side of the casing and provided with catch means, retaining guide 90 strips secured upon said horizontal rods and a plurality of sheets of heat proof material having their upper ends slidably engaged and removably associated with said guide strips, the base being formed with grooves 95 receiving the lower ends of said sheets.

In testimony whereof I affix my signature.
HARRIET G. BUFFINGTON.
